INSULATED PITCHER

John L. Carroll, 1206 Buckland Ave., Robert W. Wingerd, 742 3rd Ave., and Earl R. Baxter, 1762 Port Clinton Road, all of Fremont, Ohio

Filed Dec. 26, 1963, Ser. No. 77,922

Term of patent 14 years

(Cl. D44—21)

FIG. 2-

FIG. 1-

FIG-3-

FIG-4-

FIG. 1 is a combined side elevation and quarter sectional view of an insulated pitcher incorporating our new design;

FIG. 2 is a top plan view of the insulated pitcher shown in FIG. 1;

FIG. 3 is a front elevation of the insulated pitcher shown in FIG. 1; and

FIG. 4 is a rear elevation of the insulated pitcher shown in FIG. 1.

The essential features of the design reside in the portions shown in full lines.

We claim:

The ornamental design for an insulated pitcher, substantially as shown and described.
